UNITED STATES PATENT OFFICE.

GREENE ALLEN SMITH, OF INDIANAPOLIS, INDIANA.

COMBINATION GAS AND OIL BURNER.

977,231.

Specification of Letters Patent. Patented Nov. 29, 1910.

Application filed December 11, 1909. Serial No. 532,587.

To all whom it may concern:

Be it known that I, GREENE ALLEN SMITH, a citizen of the United States, residing at Indianapolis, in the county of Marion and 5 State of Indiana, have invented certain new and useful Improvements in Combination Gas and Oil Burners, of which the following is a specification.

This invention relates to improvements in 10 burners for burning gas as fuel in stoves and furnaces, and while the invention is not limited in its application, it is primarily intended for domestic use.

The object of the invention is to superheat 15 the gas previous to ignition, and to provide means for the thorough admixture of air with it to insure perfect combustion and a blue flame.

Another object of my invention is to utilize 20 crude or more or less refined oil for the generation of the hydrocarbon vapors or gas to be supplied in whole or in part to the gas burner.

I accomplish the objects of my invention 25 by the mechanism illustrated in the accompanying drawings, in which—

Figure 1 is a top plan view of a circular embodiment of my invention such as is 30 adapted for use in cylindrical stoves or furnaces. Fig. 2 is a detail view showing the lower part of a stove with my improved burner installed therein, the view showing the several parts in vertical section on the line 2—2 of Fig. 1. Fig. 3 is a view in vertical section of the burner and heating dome, removed from the other parts of the device, the section being on the line 3—3 of Fig. 1. Fig. 4 is a horizontal section on the line 4—4 of Fig. 2. Fig. 5 is a detail view in vertical section of a stove or furnace having 35 a rectangular fire-pot, and showing a correspondingly modified form of my device, and Fig. 6 is a detail view in horizontal section on the line 6—6 of Fig. 5.

Like characters of reference indicate like 40 parts throughout the several views of the drawings.

7 represents the side walls of a stove or furnace and 8 the bottom thereof.

50 9 is the horizontal base-plate of the main or body portion of my improved burner, upon or from which the other parts are supported. The plate 9 is supported by the walls 7 of the stove or furnace. In Figs. 1 to 4 inclusive of the drawings, I have illustrated that form of my device which is in-

tended for use in connection with a cylindrical stove, and, consequently, the plate 9 is circular in shape. It is provided with a round central opening which is surrounded by an upwardly projecting and inwardly sloping flange 10. A series of vertical and radial flanges 11 are formed integral with plate 9 and flange 10 for the purpose of strengthening the parts thus connected and 60 more particularly for the purpose of preventing the warping of parts 9 and 10 when heated to a high temperature. Supported by the radial flanges 11 is an annular vertical flange 12 of greater diameter than the flange 10, and integral with the vertical annular flange 12 is an annular horizontal plate 14 which extends inwardly of the annular flange 12 from the top portion of the latter. Connecting the parts 12 and 14 and 65 integral with them are the radial and vertical flanges 16 which register with the flanges 11 so as to form continuations of the latter. Displacement of the parts 12 and 16 is prevented by notching the flange 10 to receive the flanges 16, and by reducing the 70 height of flanges 11 to a level with the bottoms of said notches to receive flanges 16 and also to form shoulders 17 in the radial flanges 11 to retain the position of the annular flange 12.

The plate 14 has a central opening which is surrounded by an upwardly projecting rib or flange 18. Resting upon the flange 18 is a concave plate or dome 19 which has a 75 marginal vertical flange 20 which surrounds the rib or flange 18 and prevents lateral displacement of said dome 19. Extending from one side to the other of the concave plate 19 and preferably with a higher arch for its outer wall, as shown in Fig. 3, and a lower arch for its inner wall, is a superheating chamber 21, which communicates at each of its ends with vertical passages 22, and these 80 passages 22 discharge into an annular chamber 23 which is surrounded by the flange 10 and is sufficiently remote therefrom to allow for a free circulation of air between the walls of the chamber 23 and said flange 10. The outer walls of the annular chamber 23 are provided with a series of perforations 24 through which the superheated gas will be 85 discharged. Opposite each of the perforations 24 is a perforation 25 through the flange 10. The gas issuing from the chamber 23 to the holes 24 will pass on through the holes 25 and will be ignited on the out- 90 95 100 105 110

side of the flange 10. Air will be admitted from both top and bottom around the walls of the chamber 23, and as the gas passes across the open space between the flange 10 and the perforated wall of chamber 23 the air coming in above and below will mix with the gas in sufficient quantities to produce a thorough combustion of the hydrocarbon vapors. Should the heat not be sufficiently intense, it can be increased by shutting off the air from above the chamber 23 by placing a packing of asbestos between the upper walls of chamber 23 and flange 10.

26 is a gas supply pipe which discharges 15 into the superheating chamber 21. A leading-in pipe 27 from any suitable gasometer or source of supply discharges into the lower end of the pipe 26, and this lower end of pipe 26 is preferably expanded as shown in 20 Fig. 2 for the admission of air and its admixture with the gas from pipe 27, in the pipe 26 before its discharge into the chamber 21.

Located at one side of the chamber 21 is 25 a wall 30 which connects the top of chamber 21 with the lower edge of dome 19 and forming a closed chamber above said dome 19. A pipe 31 supplies oil under pressure to the last named chamber, and a pipe 32 conveys the vaporized oil from this chamber 30 and discharges it into the bottom of the pipe 26. The oil-chamber is provided with a vertical partition 33 at its major upper portion whereby the oil-chamber is divided 35 into two compartments which communicate with each other below the partition 33 thereby compelling the oil entering on one side through pipe 31 to pass down under the partition 33 and become vaporized by the intense heat of the walls surrounding this oil-chamber and to enter the discharge pipe 32 40 in vapor form. Without the partition 33 the oil would pass directly across and out through pipe 32, perhaps without being vaporized.

It will be noted that the principal parts of my device are readily separable. Thus the plate 9 with its flanges 10 and 11 only loosely support that portion comprising the 50 member 12, 14 and 16, and the dome-plate 19 with its integral and attached parts are loosely supported upon the plate 14. This enables the device to be quickly dismantled for shipment or for renewals and repairs or 55 other purposes, and to facilitate this separation, and for greater convenience and cheapness in the process of manufacture, I prefer to divide the plate 9 and flange 10 on the lines 35, and the flange 12 and plate 14 on the lines 36.

In the modification shown in Figs. 5 and 6 the superheating chamber 41 is separated from the chamber 42 from which the gas issues through the holes 43, by means of a 60 vertical partition 44 having passageways at

its ends. This partition compels the gas entering through pipe 26 to pass around the partition 44 so as to give it the maximum heat exposure. Holes 43 may be formed through the top horizontal wall of chamber 70 42 as well as through its outer vertical wall and thus the capacity of the burner may be practically doubled. The vertical flange 10' has the opening 25^a, here shown as a continuous slot, for the same purpose as previously described, and a like opening 25' will be formed in the horizontal plate above the burner. Air for mixing purposes will be supplied from two directions, that is, from below, and also from the opposite direction 80 by coming around the back of the chamber 41 as shown by the arrows in Fig. 5. The oil chamber in this modification is shown at 50 and is piped in the same manner as for the other form of the device, already described.

Having thus fully described my invention, what I claim as new and wish to secure by Letters Patent of the United States, is—

1. In a hydrocarbon burner, a distributing 90 chamber having walls with a series of gas-exit openings, a plate separated by an air-space from every adjacent wall of said distributing chamber and thereby providing an air supply, said plate having larger openings 95 which register with said exit openings of the distributing chamber, a superheating chamber connected by conduits to said distributing chamber, a mixer pipe supplying mixed air and hydrocarbon vapors to said chamber, 100 and a pipe supplying hydrocarbon vapor to said mixer pipe.

2. In a hydrocarbon burner, a distributing 105 chamber having walls with a series of gas-exit openings, a plate separated by an air-gap from every adjacent wall of said distributing chamber and thereby providing an air supply, said plate having larger openings 110 which register with said exit openings of the distributing chamber, a superheating chamber connected by conduits to said distributing chamber, a mixer-pipe supplying gas to said chamber, an oil chamber wherein oil is volatilized by the heat from the burner, 115 means for supplying oil to said oil chamber, and a pipe discharging the oil vapors from the oil chamber into said mixer pipe.

3. The combination with a stove or furnace, of a distributing chamber located 120 therein having gas exits, a superheating chamber communicating with said distributing chamber, a pipe discharging into said superheating chamber, and a partition dividing the stove into upper and lower compartments, said partition being separated by 125 an air-space from the walls of said distributing chamber and having openings through said partition opposite said gas-exits from said distributing chamber whereby an additional mixture of air will be made with the

gas as it passes across the air-space between the partition and distributing chamber.

4. The combination with a stove or furnace of an approximately horizontal partition having a central opening surrounded by an upwardly extending flange, said flange having a series of transverse gas exit holes, a distributing chamber located in the opening of said horizontal partition, said distributing chamber having perforations in its outer wall opposite the gas exit holes in said flange, said flange and distributing chamber being separated by an air-space, a superheating chamber above said distributing chamber having perforations in its outer wall opposite the gas exit holes in said flange, said flange and distributing chamber being separated by an air-space, a superheating chamber above said distributing chamber communicating with the latter, a mixer pipe supplying gas to said superheating chamber, an oil chamber wherein oil is volatilized by heat from said gas burner, means for supplying oil to said oil chamber, and a pipe discharging the oil vapors from the oil chamber into said mixer pipe.

5. The combination with a stove or furnace of an approximately horizontal partition having a central opening surrounded by an upwardly extending flange, said flange having a series of transverse gas exit holes,

a distributing chamber located in the opening of said horizontal partition, said distributing chamber having perforations in its outer wall opposite the holes in said flange, said flange and distributing chamber being separated by an air-space, a superheating chamber above said distributing chamber communicating with the latter, a mixer pipe supplying gas to said superheating chamber, an oil chamber wherein oil is volatilized by heat from said gas burner, means for supplying oil to said oil chamber, and a pipe discharging the oil vapors from the oil chamber into said mixer pipe.

In witness whereof, I have hereunto set my hand and seal at Indianapolis, Indiana, this 2nd day of December, A. D. one thousand nine hundred and nine.
